MINING DRILL

Walter Cook, Benton, Ill., assignor to Central
Mine Equipment Co., St. Louis, Mo., a corpora-
tion of Missouri

Application June 15, 1932, Serial No. 617,299
Renewed February 12, 1934

19 Claims. (Cl. 255—69)

This invention relates to mining drills, and has special reference to mining drills of the auger type.

An object of the invention is to provide improved equipment for a mining drill of the auger type whereby series of bits may be detachably secured to the end of the auger in a novel cooperative relationship, the bits comprising each series also being arranged and mounted in a novel relationship with respect to each other, so that a satisfactory and improved boring or drilling effect is obtained when the drill is operated.

Another object of the invention is to provide an improved wedge fastener of novel construction whereby the bits may be detachably secured to the end of the auger in the novel relationship indicated and hereinafter more particularly described.

Another object of the invention is to provide an improved mining drill embodying all of the novel and advantageous features, and obtaining all of the improved advantageous results, herein disclosed or otherwise made apparent from the following description, reference being made to the annexed drawing, in which—

Fig. 1 is an end elevation of the auger of a mining drill embodying and having in connection therewith my present invention.

Fig. 2 is a side elevation, a part of the auger being broken away to show more clearly the arrangement of the bit wedge and the bits in connection therewith.

Fig. 3 is a side elevation looking at right angles to Fig. 2.

Fig. 4 is an end elevation of the auger as in Fig. 1, the bits being shown in section.

Fig. 5 is an end elevation of the auger as in Fig. 1 with a reverse type of bit wedge.

Fig. 6 is a perspective view of the bit wedge illustrated in Figs. 1 and 4.

Fig. 7 is a perspective view of the bit wedge illustrated in Fig. 5.

Fig. 8 is a perspective view of one of the bits.

Fig. 9 is a perspective view of a bit having a cutting edge at each end.

Fig. 10 is a side elevation of a wedge and one of the cutting bits associated therewith showing their engaging curved walls.

Fig. 11 is an elevation of the opposite side of the wedge and associated cutting bit showing their engaging curved walls.

The detachable end member 1 of the auger is formed with a socket 2 designed and adapted to receive an extended portion of the main part of the auger and has a keyhole 3 adapted to receive

a key to secure the part 1 rigidly on the extended portion of the main part of the auger.

The forward end of the detachable end member 1 is formed with two sockets 4, the outer side walls 5 being in substantially spiral continuation of the inclined walls 6 of the ribs 7.

The two opposite walls 8 of each socket 4 converge rearwardly from the front end of the member 1, so that the rear portions of these sockets 4 are of less width than the forward portions thereof. The sockets are open at both ends, so that the wedge fasteners hereinafter described extend entirely through the sockets.

The wedge shown in Figs. 1 to 4, inclusive, and in Fig. 6 comprises a tapered body having in one corner of its forward end a notch 9 and in the diagonally opposite corner a notch 10, thus providing a wall 11 and a wall 12 integrally connected by a portion 13 and leaving the opposite end 14 of the bit wedge solid to provide a shoulder 15 at the end of each of these notches. Accordingly, the structure comprising the walls 11 and 12 and the connecting portion 13 may be described as of approximate Z-shape. The corner 16 of the wall 12 opposite the notch 10 is rounded in order to be received within a correspondingly rounded portion of the socket 4.

The side walls 17 of the sockets 4 are provided with notches 18 which are in substantial continuation of the notches 9 and 10, respectively, when the bit wedge is mounted in the socket.

The bits may be of duplicate construction. Each bit comprises an elongated body 19 that is substantially rectangular in cross section and curves forwardly, having a bevel cut 20 on its outer end 35 inclining from intersection with the rear wall to intersection with the front wall of the body 19 to provide a relatively sharp cutting edge 21. These bits fill the notches 9 and 10 and abut against the walls 15 and fill the notches 18.

In attaching the bits to the auger, a bit is placed in each of the notches 9 and 10 of each bit wedge and the assembled bits and wedge are then driven into one of the sockets 4. The wedge tapers in conformity with the taper of the socket 4 in which the wedge is mounted. When a wedge and the bits assembled in connection therewith are driven into either socket, the bits are clamped and wedged in the notches 9 and 10 and in the notches 18, a rigid wedging connection being thus secured and maintained. The ends of the bits are covered and enclosed within the sockets into which the bits extend, but the wedges extend beyond the sockets, as clearly shown in Figs. 2 and 3, so that the rear ends 14 of the wedges may be 55

struck with a hammer or other tool and driven from the sockets for any desired purpose.

The walls of the notches 9 and 10 form curved surfaces on the walls 11 and 12 in conformity with the curvature of the bit bodies 19. The outer bits, which are mounted in the notches 10 closest to the periphery of the auger, are preferably of somewhat less length than the remaining bits which are closest to the axis of the auger. The 10 sockets 4 incline outwardly and forwardly toward the periphery of the auger, so that the bits are maintained and supported in an inclined relationship with their rear ends nearer the axis of the auger than their outer ends. In fact, the 15 outer ends of the outer bits extend substantially beyond the periphery of the auger, so that the bits will cut and drill and bore a hole of substantially larger diameter than the diameter of the auger body. The bits that are closest to the 20 central axis of the auger extend forwardly beyond the lateral bits and cut and drill in advance of the ends of the lateral bits. The outer bits, which is to say the bits that are mounted in the notches 10, travel in advance of the inner bits when the 25 auger is rotated.

Thus, my invention comprises an embodiment 30 of means for supporting and wedging and clamping series of bits in detachable engagement with the forward end of an auger in a relationship in which the bits of each series are arranged to travel one in advance of the other when the auger is rotated. I consider this angular type of wedge generically new, and the novel functions that it 35 performs of offsetting the bits and strengthening the outer portion of the rear wall 17 of the socket are highly advantageous. Further, the device supports and holds the bits in an outwardly inclined and forwardly curving relationship, so that the central bits, which are the bits closest to the 40 axis of the auger, cut in advance of the outer bits, which are closest to the periphery of the auger; and the outer bits are inclined to such an extent that their cutting points extend beyond the periphery of the auger and will cut or bore or drill 45 a hole of larger diameter than the diameter of the auger.

In Figs. 5 and 7, the bit wedge is of reverse construction, the inner notch 22 being in the front side and the outer notch 23 being in the rear side 50 of the wedge body, thus forming an inner wall 24 and an offset outer wall 25 united by an integral connection 26. The inner end portion 27 of the body is solid and is without notches, the end walls 28 of the notches forming abutments against 55 which the ends of the bits engage.

A bit 29 is mounted in each notch 22 and in a corresponding notch 30 in the socket wall 31, and a bit 32 is mounted in each notch 23 and in a corresponding notch 33 in the socket wall 34.

60 These bits 29 and 32 are constructed and formed in the same manner as the bits 19, the notches 30 and 33 being in the socket walls opposite from the notches 18, so that the outer bits 32 are offset rearwardly from the inner bits 29, leaving the inner bits 29 traveling even with or possibly in advance of the outer bits 32 when the drill is rotated. The sockets in which these modified wedge members are mounted are otherwise the same as the sockets 4, the wedge members protruding beyond the sockets, so that the rear ends 65 of the wedge members may be struck with a hammer or other tool and the wedge members driven from the sockets for any desired purpose.

The bit shown in Fig. 9 comprises an elongated 70 body 36 that is substantially rectangular in cross

section and curves forwardly having a bevel cut on each end inclining from intersection with the rear wall to intersection with the front wall to provide relatively sharp cutting edges 36 and 37. These bits may be applied and attached to the end of the member 4 by seating the bit bodies 35 in the notches 9 and 10 or in the notches 22 and 23. When the protruding end of the bit becomes worn, the wedge may be driven from the socket and the bits applied in reverse position, 10 substituting the cutting edge 37 at the outer end of the bit for the end 36, or vice versa.

Obviously this invention may be varied in other particulars and may be easily designed to include any desired number of bits, and I do not restrict myself to the specific forms and configurations shown. I contemplate such variations as may adapt the invention to its intended purposes, and do not restrict myself in any unessential particulars. What I claim and desire to secure by Let- 20 ters Patent is:

1. In a mining drill having sockets in its forward end, a wedge removably seated in each of said sockets and having notches in diagonally opposite corners, and a bit mounted in each of 25 said notches and engaged against the wall of the socket and thereby locked in a relationship in which certain of said bits are in advance of the others when the drill rotates.

2. In a mining drill, walls forming sockets in 30 its forward end and having notches in certain of said walls, a wedge member mounted in each of said sockets and having diagonally opposite notches corresponding to said first named notches, and bits mounted rigidly in the notches in said 35 wedge members and said walls.

3. In a mining drill having sockets in its forward end, an approximately Z-shaped wedge mounted in each of said sockets, and cutting bits 40 mounted on opposite sides of said wedges in said sockets and clamped against the walls of said sockets.

4. A drill bit holding tool having a forward end of smaller diameter than the remaining portion, sockets in the forward end of said tool, approximately Z-shaped clamping wedges mounted 45 in said sockets and having notches in the opposite sides thereof facing the walls of said sockets, and bits mounted in said notches on opposite sides of said wedge members and clamped rigidly 50 against the walls of said sockets.

5. In a mining drill having sockets in its forward end, wedge blocks mounted in said sockets and having notches in opposite sides thereof provided with longitudinally curved walls, and longitudinally curved cutting bits mounted in said 55 notches in said wedge blocks and matching the curvature of said walls of said notches and being clamped between said wedge members and the walls of said sockets.

6. In a mining drill having forwardly diverging sockets in its forward end, diverging cutting bits extending into each of said sockets, and an angular clamping wedge clamped rigidly in each of said sockets and extending on adjacent and also on opposite sides of said bits and clamping 65 said bits in diverging relation in said sockets.

7. In a mining drill having forwardly diverging sockets in its forward end, clamping wedges rigid in said sockets and having notches in its opposite 70 sides, and cutting bits clamped in forwardly diverging relation in said sockets and in said notches on opposite sides of said clamping wedges.

8. In a mining drill having forwardly diverg- 75

5 ing sockets in its forward end, a number of forwardly diverging cutting bits extending into each of said sockets, and angular clamping wedges rigid in said sockets and engaging front and rear sides of respective cutting bits mounted in the respective sockets.

10 9. In a mining drill having forwardly diverging sockets in its forward end, a wedge removably seated in each of said sockets and having forwardly diverging notches in diagonally opposite corners, and forwardly diverging bits mounted in said notches and engaged against the walls of the socket and thereby locked in a relationship in which certain of said bits diverge forwardly 15 and are in advance of the others when the drill rotates.

15 10. In a mining drill, walls forming forwardly diverging sockets in its forward end and having notches in certain of said walls, a wedge mounted in each of said sockets and having forwardly diverging diagonally opposite notches corresponding to said first named notches, and forwardly diverging bits mounted rigidly in the notches in said wedge members and said walls.

20 11. In a mining drill having forwardly diverging sockets in its forward end, an approximately Z-shaped wedge mounted in each of said sockets, and cutting bits mounted on opposite sides of said wedges in said sockets and clamped against the walls of said sockets in forwardly diverging relationship.

25 12. A drill bit holding tool having a forward end of smaller diameter than the remaining portion, forwardly diverging sockets in the forward end of said tool, approximately Z-shaped clamping wedges mounted in said sockets and having forwardly diverging notches in the opposite sides thereof facing the walls of said sockets, and forwardly diverging bits mounted in said notches on opposite sides of said wedge members and clamped rigidly against the walls of said sockets.

30 13. In a mining drill having forwardly diverging sockets in its forward end, a wedge removably seated in each of said sockets, bits mounted in said sockets at the front side of the wedges therein adjacent to the periphery of the drill, and bits mounted in said sockets at the rear of said wedges therein closer to the axis of the drill than said first named bits.

35 14. In a mining drill, walls forming diverging sockets in its forward end, wedges mounted in said sockets respectively, and bits mounted in each of said sockets at the front and rear sides of the wedge in the sockets in which the bits are mounted.

40 15. In a mining drill having a socket in its forward end and having a groove in each of two diagonally opposite corners of said socket, a pair of bits extending into said socket and each having an edge portion extending into one of said grooves, and an approximately Z-shaped wedge member extending into said socket between said bits and between the walls of said socket and the edges of said bits respectively that are opposite said grooves and rigidly securing said bits in said positions.

45 16. In a mining drill having a tapered socket in its forward end, a wedge removably mounted in said socket and having notches in diagonally opposite portions thereof, and cutting bits extending into said socket and in said notches and thereby rigidly secured in connection with said drill in a relationship in which said bits diverge forwardly and have their forward ends spaced apart a distance in excess of the diameter of said drill.

50 17. In a mining drill having a tapered socket in its forward end, a wedge of greater length than said socket removably mounted therein and having its forward end extending beyond the forward end of said socket and having its rear end extending rearwardly beyond said socket in position to be struck to drive the wedge forwardly out of the socket and also having an elongated notch in one corner extending from its front end toward and terminating short of its rear end, and 55 a bit mounted in said socket in front of said wedge and seating in and extending the full length of said notch and against the side of the forwardly projecting end portion of said wedge and being braced thereby beyond the forward end of said socket.

60 18. In a mining drill having a tapered socket in its forward end, a wedge of greater length than said socket removably mounted therein and having its forward end extending beyond the forward end of said socket and having its rear end extending rearwardly beyond said socket in position to be struck to drive the wedge forwardly out of the socket and also having an elongated notch in one corner extending from its front end 65 toward and terminating short of its rear end, a bit mounted in said socket in front of said wedge and seating in and extending the full length of said notch and against the side of the forwardly projecting end portion of said wedge and being braced thereby beyond the forward end of said socket, and an additional bit extending into said socket at the rear of said wedge and being nearer the axis of the drill than said first named bit.

65 19. In a mining drill having a tapered socket in its forward end, a wedge of greater length than said socket removably mounted in said socket and having its forward end extending beyond the forward end of said socket and its rear end extending rearwardly beyond the rear end of said socket in position to be struck to drive the wedge forwardly from the socket and also having an elongated notch in one corner extending from its front end toward and terminating short of its rear end, and a forwardly curved bit mounted 70 in said socket in front of said wedge in and extending the full length of said notch and being braced by said wedge beyond the forward end of said socket, said bit having a beveled wall extending forwardly from its rear side to intersection with its front side and forming a cutting edge across the forward end of said bit.

75 WALTER COOK.
